UNITED STATES PATENT OFFICE

165,096

REFRIGERATOR

Peter Muller-Munk, Pittsburgh, Pa., assignor to
Westinghouse Electric Corporation, East Pitts-
burgh, Pa., a corporation of Pennsylvania

Application February 1, 1951, Serial No. 14,064

Term of patent 14 years

(Cl. D67—3)

To all whom it may concern:

Be it known that I, Peter Muller-Munk, a citizen of the United States, residing at Pittsburgh, in the county of Allegheny and State of Pennsylvania, have invented a new, original, and ornamental Design for a Refrigerator, of which the following is a specification, reference being had to the accompanying drawing, forming a part thereof:

Fig. 1 is a perspective view of a refrigerator embodying my novel design and illustrating the front and one side of the refrigerator;

Fig. 2 is a view in elevation of the side of the refrigerator in view in Fig. 1;

Fig. 3 is a view similar to Fig. 2 but illustrating the opposite side of the refrigerator;

Fig. 4 is a top plan view of the refrigerator shown in Fig. 1; and

Figs. 5, 6 and 7 are, respectively, sections taken along the lines V—V, VI—VI and VII—VII of Fig. 1 for illustrating surface contours.

I claim:

The ornamental design for a refrigerator, substantially as shown and described.

PETER MULLER-MUNK.
